(57) **CLAIM**

The ornamental design for a refrigerant manifold gauge as shown and described.

DESCRIPTION

FIG. 1 is a front, right and top perspective view of a refrigerant manifold gauge, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is another front, right and top perspective view of the refrigerant manifold gauge in another state.

The broken lines depict portions of the refrigerant manifold gauge that form no part of the claimed design. The dot-dash broken lines in FIGS. 1 and 9 depict the boundaries of the enlargements that form no part of the claimed design.
